UNITED STATES PATENT OFFICE.

PERCY B. BOSWORTH, OF SPRINGFIELD, OHIO, ASSIGNOR TO THE VICTOR RUBBER COMPANY, OF SPRINGFIELD, OHIO, A CORPORATION OF OHIO.

DESIGN FOR A PNEUMATIC-TIRE TREAD.

Application filed November 27, 1922. Serial No. 4,421. Term of patent 14 years.

To all whom it may concern:

Be it known that I, Percy B. Bosworth, a citizen of the United States, residing at Springfield, in the county of Clark and State of Ohio, have invented a new, original, and ornamental Design for Pneumatic-Tire Treads, of which the following is a specification, reference being had to the drawing forming part thereof.

Fig. 1 is a plan view of a portion of a pneumatic tire casing showing my design.

Fig. 2 is a section on the line 2—2 of Fig. 1.

I claim:

The ornamental design for a pneumatic tire tread as shown.

PERCY B. BOSWORTH.
